CLAIM

The ornamental design for the solar powered garden light with fluted glass enclosure, as shown and described.

DESCRIPTION

FIG. 1 is a front, rear, right and left view of the solar powered garden light with fluted glass enclosure of my design.

FIG. 2 is a top view of the same solar powered garden light with fluted glass enclosure as shown in FIG. 1; and,

FIG. 3 is a bottom view of the same solar powered garden light with fluted glass enclosure as shown in FIG. 1.

The broken line that defines the bounds of the claimed design forms no part thereof.
